UNITED STATES PATENT OFFICE

99,332

DESIGN FOR A REGULATOR OR SIMILAR ARTICLE

Frank E. Rice, Detroit, Mich., assignor to American Tap-Bush Company, Detroit, Mich., a corporation of Delaware

Application February 8, 1936, Serial No. 61,047

Term of patent 14 years

To all whom it may concern:

Be it known that I, Frank E. Rice, a citizen of the United States, and a resident of the city of Detroit, county of Wayne and State of Michigan, have invented a new, original, and ornamental Design for a Regulator or Similar Article, of which the following is a specification, reference being had to the accompanying drawing forming a part thereof.

On the drawing:

Figure 1 is a view of one side of the regulator or similar article embodying my invention.

I claim:

The ornamental design for a regulator or similar article, as shown.

FRANK E. RICE.
